UNITED STATES PATENT OFFICE.

LOUIS C. HENRIKSEN, OF LOS ANGELES, CALIFORNIA.

ELECTRICAL INSTANTANEOUS WATER-HEATER.

No. 890,053.

Specification of Letters Patent.

Patented June 9, 1908.

Application filed April 10, 1907. Serial No. 367,322.

To all whom it may concern:

Be it known that I, LOUIS C. HENRIKSEN, a citizen of the United States, residing at Los Angeles, in the county of Los Angeles and 5 State of California, have invented new and useful Improvements in Electrical Instantaneous Water-Heaters, of which the following is a specification.

My invention relates to an instantaneous 10 electrical water heater in which a plurality of resistance coils are used to heat water; and an object thereof is to provide a heater of small and compact form which may be utilized in heating water to the required temperature instantly. I accomplish this object 15 by means of the device described herein and illustrated in the accompanying drawings, in which—

Figure 1— is a central vertical section of 20 my heater taken on line 1—1 of Fig. 2. Fig. 2— is a cross section of my heater taken on line 2—2 of Fig. 1. Fig. 3— is a plan view of one of the electrical heating elements. Fig. 25 4— is a perspective view of my complete device.

Referring to the drawings, 5 designates a metallic casing closed on all sides, the back plate 6 being removable so that ready access may be had to the interior. Arranged with- 30 in this casing is a waterway 7 which is preferably formed of copper tubing and bent to form a plurality of coils 8; the inlet 9 of the waterway enters approximately at the bottom of the casing and the outlet 10 termin- 35 nates outside of the casing on the front face thereof. I have illustrated this waterway in the form of a series of spiral coils, but other arrangements and dispositions may be made without departing from the spirit of my in- 40 vention, the main object being to obtain as long a waterway as is possible and still retain the casing in a small and compact form. The inlet to the waterway 7 is connected to a 45 source of supply (not shown) by a flexible pipe 11.

Secured in a suitable manner in the in- 50 terior of the casing and interposed between the coils 8, as is best illustrated in Fig. 2 of

the drawings are a plurality of electrical heating elements 12 preferably resistance 50 coils, being connected together in series and terminating on the outside of the casing and connected to an electric socket 13 of any desired form. The resistance coils may be connected to a source of electrical energy (not 55 shown) by means of plugs 14. The interior of the casing is filled with a heat conserving and electric insulating material 15, preferably asbestos as I have found that that material retains the heat the longest. 60

It will be observed that by arranging the coils of the waterway closely together and interposing a resistance between the adjacent coils I am enabled to apply the heat generated by the current passing through the 65 coils to the best advantage, thus heating the waterway in the minimum amount of time.

It will be further observed from the above description that I have provided a device which is small and compact in form and one 70 that is portable and which may be used in various situations, such as kitchen sinks, bath tubs, wash bowls and other places where hot water is required.

Having described my invention what I 75 claim as new and desire to secure by Letters Patent is:—

An electrical water heater comprising a metallic casing, a heat conserving material completely filling said metallic casing, a 80 water conductor comprising a plurality of coils arranged one above the other, and spaced apart from each other within said heat-conserving material, an electrical conductor comprising a plurality of coils, one of 85 said coils being positioned adjacent each of the water conductor coils, but spaced therefrom by said heat-conserving material.

In witness that I claim the foregoing I have hereunto subscribed my name this 2nd day 90 of April, 1907.

LOUIS C. HENRIKSEN.
